UNITED STATES PATENT OFFICE.

GREGORY CALDWELL DAVISON, OF NEW LONDON, CONNECTICUT, ASSIGNOR TO ELECTRIC BOAT COMPANY, OF NEW YORK, N. Y., A CORPORATION OF NEW JERSEY.

FUEL-SUPPLY SYSTEM FOR INTERNAL-COMBUSTION ENGINES.

1,236,060.

Specification of Letters Patent.

Patented Aug. 7, 1917.

Application filed June 24, 1913. Serial No. 775,510.

To all whom it may concern:

Be it known that I, GREGORY C. DAVISON, a citizen of the United States, residing at and whose post-office address is New London, county of New London, State of Connecticut, have invented certain new and useful Improvements in Fuel-Supply Systems for Internal-Combustion Engines; and I do hereby declare the following to be a full, clear, and exact description of the invention, such as will enable others skilled in the art to which it appertains to make and use the same.

The object of the invention is to provide a simple and efficient fuel supply system for multiple cylinder internal combustion engines, and it has been applied particularly to feeding liquid fuel to the several cylinders of multiple cylinder oil engines of the Diesel type. The invention in its preferred embodiment is characterized by the employment of a single fuel pump driven from the engine at a constant stroke and of sufficient capacity to deliver a quantity of fuel in excess of the amount required to supply the cylinders; an intermediate pressure chamber in which the fuel discharged from the pump is maintained at a constant pressure and from which the excess fuel is returned to the suction side of the pump; a suitably controlled throttle valve commanding the outlet from the pressure chamber; and a system of supply pipes beyond the throttle valve and leading to the cylinder fuel inlet valves; whereby the fuel is supplied at the same pressure to all of the said inlet valves and each working cylinder is caused to carry its proper proportion of the load at all times.

In the preferred embodiment of the invention the predetermined pressure in the pressure chamber is established by the spray air employed to inject the fuel into the cylinders.

In the accompanying drawings, illustrating this preferred arrangement within the invention—

Figure 1 illustrates somewhat diagrammatically partly in section and partly in elevation the general arrangement of the apparatus;

Fig. 2 illustrates the relation of the governor to the throttle valve;

Fig. 3 is a section through the pressure chamber on the line 3—3 of Fig. 4;

Fig. 4 is a sectional plan on the line 4—4 of Fig. 7 showing the relative arrangement of the pump, pressure chamber and throttle valve;

Fig. 5 is a section on the line 5—5 of Fig. 2 further illustrating the construction and arrangement of the governor;

Fig. 6 shows in front elevation the hand control;

Fig. 7 is a vertical section through the pump, pressure chamber, connecting conduit and auxiliary hand pump for starting; and

Fig. 8 is a plan of the same parts.

The shaft 1 is driven from the engine by appropriate operating connections, and it carries an eccentric 2 for reciprocating the plunger of the fuel pump 3 at a constant stroke. This pump supplies fuel for all the cylinders, irrespective of their number, and when driven at a constant speed it supplies the fuel, at a constant rate equal to or greater than that required for the maximum load, to the pressure chamber 9. The fuel pump draws oil from the oil tank 4 through the pipe 5 and the suction check valve 6 and forces it past the discharge check valve 7 and through the conduit 8 into the lower part of the pressure chamber 9 below the floating piston 10 therein. The upper face of the piston 10 is in communication through the pipe 11 with the reservoir 12, which is furnished with air at constant pressure by means of the compressor 13, connected thereto through the cooler 14 and the pipes 15 and 16 fitted with the check valve 17 according to well known practice. (See Fig. 1). In this way the piston 10 floats between two pressure columns, oil on the bottom and air on the top, so that if the oil pressure is the greater the piston rises until the port 18 is uncovered to return a part of the oil from the lower part of the intermediate reservoir to the suction side of the fuel pump 3. When the oil pressure decreases the piston 10 is forced down by the air column until the overflow port 18 is partly or entirely covered. In this way the pressure on the fuel in chamber 9 is maintained constant and proportional to the injection air pressure in the tank 12.

The pressure chamber 9 is constantly in communication with the throttle valve through duct 21. The longitudinally movable throttle valve rod 24 fits tightly within

the open bore of the casing 20 except at the reduced portion 25 which registers with the conduit 21 and the outlet duct 22, and serves to throttle the passage of oil from the chamber 9 to the manifold 32, in accordance with its position in the casing. The valve herein shown is pressure balanced at all positions and therefore may be moved up or down with equal facility and without binding.

The mechanism for controlling the position of the throttle valve is of well known construction, and provides for automatic control by the governor to limit the speed and prevent racing, and for hand control at speeds less than that for which the governor is set. For this purpose the valve 24 is connected by the link 26 to the floating lever 27 having a fulcrum at 28 which may be shifted by hand, and connected at the other end to governor rod 29. Upon occurrence of excess speed the governor rod 29 lifts lever 27, which turns on fulcrum 28 and lifts the valve rod 24 to decrease or shut off the supply of fuel. If it is desired to reduce the speed by hand control the crank 31 (see Fig. 6) is manipulated to turn eccentric 32 and lift the link 33. This lifts the floating lever 27, which now turns on the upper end of governor rod 29 as a fulcrum, and throttles the feed.

The governor herein illustrated comprises the two weighted arms 34 pivoted at 35 to the fly wheel 36 and adapted to respond to centrifugal force against the stress of the springs 37. (See Figs. 2 and 5). Upon variation of the speed of the engine, the arms act in unison to turn the collar 38, which has a helical groove or cam slot, relatively to the hub of the fly wheel, which has the projecting pins 39 entering said groove or slot. Thus the collar 38 is shifted in the direction and by an amount determined by the radial movement of the arms resulting from the change of speed, and the pivoted bell crank 40 is swung one way or the other to raise or lower the governor rod 29 and the floating lever 27.

The oil passes from the throttle valve through the pipe 23 to the manifold 32 and is distributed to the individual cylinder inlet valves through the several feed pipes 33. The oil is sprayed into the cylinder against the compression therein by the air from the reservoir 12, and is ignited to effect the operation of the engine in the well known way.

The hand pump 41 is provided for the purpose of initiating the oil supply for starting the engine from rest.

Having thus described my invention what I claim is:

1. A fuel-supply system for multiple cylinder internal combustion engines having individual fuel feed valves for the several

cylinders, and a common source of supply for said valves including a pump, a pressure chamber into which the pump discharges and from which the excess oil is returned to the suction side of the pump, means for maintaining a constant pressure on the fuel in said chamber, a feed conduit leading from said chamber, branch conduits connecting with said feed conduit and through which fuel is supplied to the fuel feed valves of the engine cylinders, and a single throttle valve common to all the cylinders controlling said feed conduit in advance of said branches, whereby fuel is supplied from the common pump to the several cylinders at a uniform pressure controlled by the throttle valve.

2. A fuel-supply system for multiple cylinder internal combustion engines having individual fuel feed valves for the several cylinders, a compressed air supply for injecting the fuel at said valves, and a common source of fuel supply for said valves including a pump, a pressure chamber into which the pump discharges and from which the excess oil is returned to the suction side of the pump, means for applying to the fuel in said chamber the pressure of the injection air supply, a feed conduit leading from the said chamber and through which fuel is supplied to the fuel feed valves of the engine cylinders, and a throttle valve controlling said conduit, whereby fuel is supplied from the common pump to the several cylinders at a pressure proportional to the injection air pressure controlled by the throttle valve.

3. A fuel supply system for multiple-cylinder internal combustion engines having individual fuel feed valves for the several cylinders, a compressed air supply for injecting the fuel at said valves, a common source of fuel supply for said several cylinders, means for maintaining said fuel supply under constant pressure comprising a pressure chamber, a piston working against the fuel in said chamber, connections between the opposite side of the piston and the compressed air supply, connections between said pressure chamber and each of said individual feed valves and a throttle valve common to all said cylinders for regulating the quantity of fluid delivered to each feed valve from said pressure chamber.

4. A fuel supply system for multiple-cylinder internal combustion engines having individual fuel feed valves for the several cylinders, a compressed air supply for injecting the fuel at said valves, a common source of fuel supply for the several cylinders, means for maintaining said fuel supply under constant pressure comprising a pressure chamber, a differential piston having its smaller head working against the fuel in said chamber, connections between

the compressed air supply and the larger head of the piston whereby the fuel is subjected to a greater pressure than the air pressure, and connections between said pressure chamber and each of said individual fuel feed valves.

5. A fuel supply system for multiple-cylinder internal combustion engines having individual fuel feed valves for the several 10 cylinders, a common fuel supply for all said cylinders, means for maintaining the fuel under constant pressure at all times, a main feed conduit leading from said supply, branch conduits from said main conduit to 15 each of said individual feed valves, and a single throttle valve common to all cylinders in said main conduit between said fuel supply and said branches for equally varying the quantity of fuel delivered to 20 each cylinder.

6. A fuel supply system for multiple-cylinder internal combustion engines having individual fuel feed valves for the several cylinders, a common fuel supply for all said 25 cylinders, means for maintaining the fuel under constant pressure at all times, a main feed conduit leading from said supply, branch conduits from said main conduit to each of said individual feed valves, a single, 30 pressure-balanced throttle valve common to

all cylinders in said main conduit between said fuel supply and said branches for equally varying the quantity of fuel delivered to each cylinder, and a centrifugal governor driven by the engine shaft operatively connected to said throttle valve.

7. A fuel supply system for multiple-cylinder internal combustion engines having individual fuel feed valves for the several cylinders and a compressed air supply for 40 injecting the fuel at the valves, a common fuel supply for all said cylinders, means operated from the air supply for maintaining the fuel under constant pressure at all times, and greater than the pressure of the 45 air supply, a main feed conduit leading from said supply, branch conduits from said main conduit to each of said individual feed valves, a single throttle valve common to all cylinders from said main conduit between said fuel supply and said branches for 50 equally varying the quantity of fuel delivered to each cylinder.

In testimony whereof I affix my signature in presence of two witnesses.
